Primary Examiner — Michael A Pratt(74) *Attorney, Agent, or Firm* — Schwabe, Williamson & Wyatt(57) **CLAIM**

The ornamental design for a bolt release catch for firearm, as shown and described.

DESCRIPTION

FIG. 1 is a perspective view of a bolt release catch. FIG. 2 is a front view of the bolt release catch of FIG. 1. FIG. 3 is a left side view of the bolt release catch of FIG. 1; and,

FIG. 4 is a right side view of the bolt release catch of FIG. 1.

The broken lines are included for the purpose of illustrating portions of the article and form no part of the claimed design.
